UNITED STATES PATENT OFFICE.

JAMES W. RANKIN, OF CYNTHIANA, KENTUCKY, ASSIGNOR OF ONE-HALF
TO WILLIAM D. TRIMNELL, OF SAME PLACE.

BADGE.

SPECIFICATION forming part of Letters Patent No. 666,024, dated January 15, 1901.

Application filed May 10, 1900. Serial No. 16,215. (No model.)

To all whom it may concern:

Be it known that I, JAMES W. RANKIN, a citizen of the United States, residing at Cynthiana, in the county of Harrison and State 5 of Kentucky, have invented certain new and useful Improvements in Badges; and I do hereby declare the following to be a full, clear, and exact description of the invention, such as will enable others skilled in the art to 10 which it appertains to make and use the same.

This invention relates to the class of metal personal wear generally known as "badges" and worn as insignia of authority or to denote 15 membership of a particular confraternity, organization, society, and the like or purely for ornamentation. It is desirable to combine with this class of articles an emblem which is normally concealed and adapted to be projected into view by a spring when released, said emblem consisting of either a plate of 20 determinate design or a plate bearing an inscription, representation, or the like, according to the particular use and purpose for 25 which the badge is designed. The badge may have an interrogatory clause inscribed thereon and the emblem bear an answer thereto, or companion and complementary representations may appear on both the badge and 30 the movable emblem or plate. The badge is admirably adapted for campaign and advertising purposes, as matters and representations can be applied to the plate and suddenly projected into view, thereby creating 35 startling effects and affording much amusement.

For a full description of the invention and the merits thereof, and also to acquire a knowledge of the details of construction of 40 the means for effecting the result, reference is to be had to the appended description and drawings hereto attached.

While the essential and characteristic features of the invention are necessarily susceptible of modification, still the preferred embodiment of the invention is illustrated in the accompanying drawings, in which—

Figure 1 is a front view of a badge embodying the invention, the dotted lines showing 45 the emblem projected. Fig. 2 is a rear view

of the badge. Fig. 3 is a rear perspective view of the badge, showing the emblem projected. Fig. 4 is a detail section of the badge about on the line X X of Fig. 2. Fig. 5 is a perspective view of the emblem. Fig. 6 is a 55 perspective view of the pin-catch guide and spring-retainer for holding the parts in place.

Corresponding and like parts are referred to in the following description and indicated in all the views of the drawings by the same 60 reference characters.

The body 1 of the badge may be of any design, shape, and configuration, and, as shown, is in the form of a button and is provided at its rear side with a reentrant edge portion 2 65 to present a finished appearance and provide means for holding the emblem and parts co-operating therewith in place. The emblem 3 is preferably a plate suitably adorned and shaped according to the caprice of the designer and is mounted so as to slide behind the body of the badge, so as to be normally concealed from view. This plate may be provided with any suitable inscription or representation, which is brought into view when 70 the emblem is projected. Ears 4 are pressed from the body of the emblem or plate 3 and are apertured to receive a guide 5, upon which it is slidingly mounted. A side portion at the inner end of the plate is separated 75 by means of a slit from the body portion and is bent inward to provide a spring-tongue 6, which bears against the inner or rear side of the body 1, for a purpose presently to be explained. The inner end of the plate 3 at the 80 opposite side is bent, as shown at 7, to provide a lip for engagement with the notch 8 of a spring-catch 9. The spring-tongue serves to hold the lip 7 in engagement with the catch 9 and to cause it to engage with the notch 8 85 when the plate or emblem 3 is pressed inward.

The catch 9 extends parallel with the guide 5, and these parts are formed of wire substantially in the manner shown. The free 90 end of the catch 9 is bent outward, as shown at 10, thence laterally across the guide 5, as shown at 11, to provide a presser-bar to present an extended surface to come in contact with the clothing and insure the release of 100

the plate or emblem when pressure is brought to bear upon the badge. A coil-spring 12 is mounted upon the guide 5 and serves to project the emblem or plate 3 when released from the catch 9.

5 The pin 13 for securing the badge to the clothing preferably extends across the guide 5 and catch 9 and is in a different plane therefrom, so as not to interfere with the free 10 movements of the plate 3 and catch 9. The spring-retainer 14, as shown, is about three-fourths of a circle and engages with the re-curved edge portion 2 of the body of the badge by a spring action. The spring-retainer 14, pin 13, catch 9, guide 5, and pressure-bar 11 are integral parts of a single wire 15 bent into the form substantially as shown. The guide 5 and catch 9 are connected at the end remote from the presser-bar 11, as shown 20 at 15, and the pin 13 is thrown outward from the plane of the parts 14, 5, and 9 by the offset portions 16. It is to be understood that the spring-retainer may be of such shape conformable to the design of the badge as to secure the emblem and adjunctive parts to the 25 badge without extraneous fastenings.

When the component parts of the badge are properly assembled, the plate or emblem 3 is pressed inward and normally concealed 30 by the body of the badge, and is held in this position by the notch 8 and lip 3. When it is required to expose the emblem, the button or badge is pressed upon to effect a release of the catch, when the spring 12, being liberated, 35 expands and projects the emblem beyond the badge, as shown by the dotted lines in Fig. 1, thereby bringing to view the inscription, picture, or other matter imprinted thereon.

Having thus described the invention, what is claimed as new is—

1. In combination with a badge, a guide, a spring-actuated catch disposed at one side of and parallel with the guide, an emblem slidely mounted on the guide and catch and held in a withdrawn position in the rear of the badge by the said catch, and a spring for 45 projecting the emblem into view when released, substantially as described.

2. In combination with a badge and a centrally-disposed guide, an emblem slidely mounted upon the said guide and provided at one side with a spring-tongue and at the opposite side with a lip, a catch to engage with the said lip and hold the emblem concealed in rear of the badge, and a spring 55 mounted upon the said guide and adapted to project the emblem into view when released from the said catch, substantially as set forth.

3. In combination with a badge having an inturned portion, and a slidely-mounted 60 emblem, a single wire bent to provide a retainer between its ends to engage by a spring action with the inturned portion of the badge, and having an end portion bent inward, thence outward to form a guide and a catch 65 in parallel relation, and having the opposite end portion bent about at a right angle to the guide and catch to form an attaching-pin, substantially as described.

In testimony whereof I affix my signature 70 in presence of two witnesses.

JAMES W. RANKIN. [L. S.]
